His Attorney.

UNITED STATES PATENT OFFICE.

CHRISTIAN STEENSTRUP, OF SCHENECTADY, NEW YORK, ASSIGNOR TO GENERAL ELECTRIC COMPANY, A CORPORATION OF NEW YORK.

METHOD OF AND FURNACE FOR UNITING METAL PARTS BY FUSION.

Application filed May 29, 1926. Serial No. 112,716.

The present invention relates to the method of uniting metal parts by fusion, using for the purpose a metal of lower melting point such as copper for example, and also 5 to a furnace for carrying out said method and in which a non-oxidizing atmosphere is maintained.

In uniting metal parts made of steel for example, in this manner they are commonly 10 tightly or closely fitted to each other so as to render the spaces or joints between them of a capillary nature. After this is done, it is the custom to temporarily clamp the parts in their proper positions one with respect to 15 the other. It is also the practice to place a heavy weight on the parts to be united in such manner as to prevent the parts from warping and to force them into intimate contact when softened by heat. This weight 20 which is made of metal is necessarily heavy and being within the furnace a great deal of heat is absorbed thereby, heat which is expensive, being obtained from electricity through suitable means such as resistors. 25 Further, the weight is inconvenient to handle and the handling is, of course, additional to the necessary work, and requiring as it does an extra operation both in loading and unloading the furnace.

I have invented or discovered a way 30 whereby for certain classes of work these independent weights may be dispensed with and the articles themselves utilized to furnish the necessary force or pressure to ensure proper contact pressure between the parts which are to be united.

Viewed from another and somewhat broader aspect, my invention comprises a continuous fusing process in which the articles 40 to be treated are fed into an elongated furnace chamber at one end and are removed as finished articles at the other, said articles in their passage through the chamber being maintained in firm contact with each other so that distortion of the parts undergoing treatment is prevented and so 45 that complete union of the parts which are to be united is effected.

My invention is particularly applicable to 50 flat plates having internal chambers and which are used for heating and cooling purposes. Such plates have wide application in the mechanical arts and one particular application is in electric household refrigerators. My invention is primarily useful

where each element is a duplicate or substantial duplicate of the others and for production of these elements in large quantities.

In carrying out my invention the elements 60 to be fused are prepared in any suitable manner with the necessary amount of copper and in this respect I may follow the present practice. Considering the case of heating and cooling plates which are made 65 of steel, have flat top and bottom plates, rather thin and of considerable surface area between which are located suitable spacers to form internal chambers. These are piled one on top of the other in a tower-like furnace, the interior of which is suitably fitted 70 with electric resistors. The top and bottom of the tower are closed and a controlled supply of hydrogen admitted thereto and a pressure maintained therein which is slightly 75 above atmosphere to prevent entrance of air. Assuming the furnace to be properly charged, the fused or finished plates are removed one by one from the bottom of the stack and the unfinished, cold plates which 80 are to be fused are fed one by one into the tower at the top. For both these purposes suitable means are provided which in addition to their function as loading and unloading devices, may also serve to prevent the 85 escape of the non-oxidizing gas and the entrance of air to the heating chamber.

The heating resistors surround the articles or elements to be treated and by preference do not extend quite to the top or to the bottom of the furnace. This means that the lowest plates will pass through a cooler region before being removed, and the articles at the top will have a chance to gradually increase in temperature before entering the hot zone where the resistors are located. The weight of the articles above those which are at fusion temperature is sufficient to firmly press the parts of the latter into firm contact and because they pass from the hot zone into one below which is enough cooler 95 to permit the fusing metal to harden, the bottom plate of the stack can be readily removed. To prevent the plates from being accidentally fused together suitable, non-fusing spacers are provided between each pair of plates wherever necessary.

In the accompanying drawing I have 100 illustrated a type of furnace designed to operate in accordance with my invention. For 105 110

- simplicity it is shown in a somewhat dia-
grammatic manner, Fig. 1 showing the fur-
nace in vertical section and Fig. 2 a cross-
section on line 2—2, of Fig. 1.
- 6 1 indicates a metallic shell or casing of
cylindrical or other form depending upon
the shape of the plates and standing on one
end. It is heavily lined with heat-insulat-
ing material 2. About the middle portion
10 thereof is located the electric resistors 3
which are supplied with current from a suit-
able source. It will be noted that they do
not extend to the top or to the bottom of the
furnace chamber so that the unfinished ar-
15 ticles to be fused are gradually heated as
they descend into the hot zone and are gradu-
ally cooled as they leave it so as to permit
the fusing metal to harden. The resistors
may be connected in any suitable manner to
20 a source of current supply and the amount
of current admitted is subject to ordinary
control devices. The zones above and below
the resistors may be made longer or shorter
depending upon the character of the articles
25 to be treated.

At the bottom of the furnace is a rectan-
gular reciprocating slide 4 of about the
width of the articles 5 which in this case are
chambered plates. At the rear of the slide
30 is a shoulder 6 adapted to engage one plate
at a time. As the slide is moved to the right
the article at the bottom of the stack is
moved with it to one side of the furnace
where it can be removed. The slide is also
35 provided with a flat portion 7 which sustains
the stack during the withdrawing or unload-
ing operation. Upon pushing the slide back
to its normal position the stack drops to
the lower part of the slide and occupies the
40 position shown. The slide may be actuated
by hand or power depending upon the
weight of the articles in the stack. As
shown, it is actuated by a double rack and
pinions. To preserve the alignment of the
45 articles in the stack suitable guides 8 are or
may be employed. These may be made of
chromium steel which does not fuse with
copper.

- In order to load the furnace a work table
50 9 is situated at one side of the furnace. On
the top of the furnace is a second rectangu-
lar slide 19 and which is provided with an
electro-magnet 11 by means of which the ar-
ticles 5 can be picked up from the table when
55 the slide is moved to the right to such posi-
tion that the magnet registers with the arti-
cle. The magnet on being energized picks
up the article after which the slide is pushed
back and the circuit of the magnet opened
60 by a switch which permits the article to drop
on the stack. This slide may be operated by
hand or by power as desired. When oper-
ated by power the arrangement used for the
lower slide may be employed. By making
65 reasonably good fits both of the slides will

prevent the escape of gas from the furnace
and the admission of air during the loading
and unloading operations.

Hydrogen or other gas is admitted to the
furnace by the conduit 12 subject to the con-
trol of a valve 13. The pressure of the gas
within the furnace should be slightly above
that of the atmosphere to prevent the en-
trance of air.

In order to prevent the articles from be-
ing fused to each other should there be an
excess of copper, spacers 14 are placed be-
tween them. For this purpose a sheet of
non-fusing metal, asbestos or equivalent ma-
terial may be used and placed on top of each
article when in the work or loading table, 9.

What I claim as new and desire to secure
by Letters Patent of the United States, is:

1. The method of uniting articles by fu-
sion of metal by a continuous process which
comprises arranging the articles and the nec-
essary fusion metal in a stack within a fur-
nace, removing fused articles from one end
of the stack and adding unfinished articles
to the other end thereof, maintaining end-
wise pressure on the stack to cause firm seat-
ing of the parts of the articles to be fused,
and maintaining a non-oxidizing atmosphere
within the furnace.

2. The method of uniting articles by fu-
sion of metal which comprises arranging the
articles and the necessary fusion metal in a
stack within a furnace whereby the weight
of the upper portion of the stack exerts pres-
sure on the articles below, heating articles in
the stack to fusing temperature, and remov-
ing the fused articles from the lower end of
the stack.

3. The method of uniting articles by fu-
sion of metal which comprises arranging the
articles and the necessary fusion metal in a
vertical stack within a furnace whereby the
weight of the upper portion of the stack exerts
pressure on the articles below, heating a
portion of the stack to fusing temperature,
maintaining an atmosphere of non-oxidizing
gas around the stack, and removing the
fused articles from the lower end of the
stack.

4. The method of uniting articles by fu-
sion of metal which comprises arranging the
articles and the necessary fusion metal in a
vertical stack within a furnace whereby the
weight of the upper portion of the stack exerts
pressure on the articles below, heat-
ing the articles in the stack to fusing tem-
perature as they descend, maintaining an at-
mosphere of non-oxidizing gas around the
stack, removing fused articles from the bot-
tom end of the stack, and adding articles to
be fused at the top.

5. The method of fusing metal articles,
each comprising two or more pieces, which
comprises assembling the partially completed
articles and fusion metal in a vertical stack

within a closed furnace, with non-fusing spacers between the articles, whereby the weight of the articles on the upper portion of the stack exert pressure on those in the lower portion, heating the intermediate portion of the stack to fusing temperature, maintaining a supply of selected gas within the furnace to facilitate fusion and prevent oxidization, removing the finished articles from the bottom of the stack after the fusing metal has hardened, and adding articles to the top of the stack as the finished articles are removed.

6. The method of fusing metal articles, each comprising two or more pieces which comprises assembling the articles and the fusing metal in a stack, whereby the weight of the articles in the upper part of the stack exert pressure on the heated articles in the lower part of the stack, slowly moving the articles into and out of a hot zone in the furnace, maintaining a non-oxidizing gaseous atmosphere within the furnace, removing finished articles from the bottom of the stack, and supplying unfinished articles to the top of the stack.

7. In an electric furnace, the combination of a member which has an elongated chamber to receive a stack of articles to be treated, electric heating elements located within the chamber and which surround a portion of the stack, means for removing articles from one end of the stack, other means for adding articles to the other end of the stack, and means for maintaining a non-oxidizing atmosphere around the articles and the heating elements.

8. In an electric furnace, the combination of a vertical member which has a central opening to receive a stack of articles to be treated, heating elements located in the member and about the articles to be treated, a means for removing the finished articles from the bottom of the stack, and means for adding articles to the top of the stack as the finished articles are removed.

9. In an electric furnace, the combination of a vertical member which has a central opening to receive a stack of articles to be treated, electric resistors which surround the middle portion of the stack for heating it

and so arranged that as the articles descend their temperature will be gradually increased to the maximum required and later decreased, a means for sliding the finished articles from the bottom of the stack, and means for lowering unfinished articles on top of the stack.

10. In an electric furnace, the combination of a vertical member which has a central opening to receive a stack of articles to be treated, electric resistors which surround the middle portion of the stack for heating it and so arranged that as the articles descend their temperature will be gradually increased to the maximum required and later decreased, a slide for pulling the finished articles from the bottom of the stack, and a means for picking up the articles, moving them into register with the top of the stack, and then lowering them.

11. In an electric furnace, the combination of a member which has an elongated chamber to receive a stack of articles to be treated, electric heating elements located within the chamber and which surround a portion of the stack, means for removing articles from one end of the stack, other means for adding articles to the other end of the stack, guiding means for directing the added articles to their proper positions in the stack and to preserve their respective positions, and a controllable means for maintaining a non-oxidizing atmosphere within said chamber.

12. The method of uniting the parts of composite metal articles by fusion of metal, which comprises arranging the articles in stacked formation and with the parts assembled, together with suitable fusing metal, in a furnace chamber which directs movement of the stack in a vertical direction, causing the stack to move by removing articles from one end of the stack and adding articles to the other end of the same, maintaining a non-oxidizing atmosphere in the furnace chamber, and heating the articles in the stack progressively as they move through the chamber.

In witness whereof, I have hereunto set my hand this 28th day of May, 1926.

CHRISTIAN STEENSTRUP.
